DESIGN FOR A COMBINATION GLASS DISH, COVER, AND BASE

Louis Poglein, Jeannette, Pa., assignor to McKee
Glass Company, Jeannette, Pa., a corporation of Pennsylvania

Application June 4, 1941, Serial No. 101,286

Term of patent 3½ years

To all whom it may concern:

Be it known that I, Louis Poglein, a citizen of the United States, residing in Jeannette, Westmoreland County, and State of Pennsylvania, have invented a new, original, and ornamental Design for a Combination Glass Dish, Cover, and Base, of which the following is a specification, reference being had to the accompanying drawing, forming part thereof, in which:

Fig. 1 is a top plan view of a combination glass dish, cover, and base, showing my new design; and Fig. 2 a side elevational view partially in cross-section thereof.

I claim:

The ornamental design for a combination glass dish, cover, and base, as shown.

LOUIS POGLINE.
